UNITED STATES PATENT OFFICE.

PETER H. BENDER, OF MINNEAPOLIS, MINNESOTA.

DESIGN FOR A COMBINATION FOOD SERVER.

Application filed June 2, 1928. Serial No. 26 972. Term of patent 7 years.

To all whom it may concern:

Be it known that I, PETER H. BENDER, a citizen of the United States, and a resident of Minneapolis, in the county of Hennepin, and State of Minnesota, have invented a new, original, and ornamental Design for a Combination Food Server, of which the following is a specification, reference being had to the accompanying drawing, forming part thereof.

I claim:—

The ornamental design for a combination food server, as shown.

PETER H. BENDER.
